LICKERIN AND FEED ROLL COVER

Roger S. Brown and August L. Miller, New Orleans, La., assignors to the United States of America as represented by the Secretary of Agriculture

Filed Aug. 1, 1958, Ser. No. 752,678

4 Claims. (Cl. 19—105)

(Granted under Title 35, U.S. Code (1952), sec. 266)

A non-exclusive, irrevocable, royalty-free license in the invention herein described, throughout the world for all purposes of the United States Government, with the power to grant sublicenses for such purposes, is hereby granted to the Government of the United States of America.

This invention relates to improvements in textile carding machines. More particularly, this invention relates to an improved type of lickerin cover which also covers the feed roll and improves the cleaning action of the lickerin and reduces the loss of spinnable fiber below the lickerin of the carding machine.

Conventional carding machines consist essentially of a lickerin to pluck small tufts of staple fiber from a bat of fibers, a carding cylinder onto which the fibers are deposited by the lickerin, a plurality of flat bars which surround about one-third of the peripheral surface of the carding cylinder, and a doffer which removes the fibers from the cylinder. The principal function of a carding machine is to separate the fibers and form a strand in which the fibers are relatively parallel. The carding machine however, is a very good cleaning machine and is depended upon to remove all leaf, seed particles, and tangled fibers not previously removed by the cleaning machines. This cleaning in the carding machine is accomplished by the mote knives below the lickerin and by the impacting of trash and fibers in the needles of the cylinder and flats. The resulting waste is periodically removed and disposed of. This waste is not all trash but contains a large percentage of good fiber. It is that part of the waste removed by the mote knives and the lickerin to which this invention is related.

It is the object of this invention to decrease the amount of fiber loss in this waste and at the same time increase the amount of cleaning accomplished by the mote knives.

The prevention of spinnable fiber being lost in the waste below the lickerin is of particular advantage. This waste, known as "motes and fly" is generally a total loss for a textile mill. A saving in spinnable fiber from this waste of approximately 0.4 percent of the total cotton processed, as has been found possible with this invention, is therefore appreciable.

It has long been the desire of many textile manufacturers to operate their carding machines with greater lickerin speeds to achieve a better quality product. One of the prime objections, however, has been the increase in loss of good fiber below the lickerin as the speed increased. One of the major causes of this increased loss has been found to be the increase of air pressure by the lickerin above the nose of the feed plate. The device, which is the object of this invention, eliminates the cause of this loss by allowing the air to escape and by keeping the air pressure relatively constant above the nose of the feed plate at all lickerin speeds. Higher lickerin speeds are thereby permitted with a minimum loss of good fiber, and with full realization of the benefits otherwise derived.

In general, the objects of this invention are achieved

2

by replacing the conventional lickerin cover and scavenger roll with a scientifically contoured cover which fits over the lickerin and extends over the feed roll and down to the fiber lap being fed into the machine. The device which is the object of this invention reduces the air pressure above the lickerin by allowing the air to filter through the fiber lap. The contoured cover may have a hinged section to permit access to the feed roll, and an adjustable end piece for setting the desired clearance to the feed plate.

The invention is described in detail below, reference being made to the accompanying drawings in which:

Figure 1 is a sectional view of the back end of a conventional carding machine.

Figure 2 is the same sectional view as Figure 1 showing the relationship between the new cover and the old elements of the carding machine, and the lap of fiber being fed into the machine.

Figure 3 is an exploded view in isometric of that part of the cover which extends over the feed roll, showing the end closure pieces, and hinged section of the cover plate, and the adjustable edge bulb for regulating the pressure on the lap.

Figure 4 is an end view of the cover shown in Figure 3.

Figure 5 is a plan view and Figure 6 is an elevation of the end closure piece.

Figure 7 is an end view of the cover plate at the closure piece, showing the hinged section of the cover plate in the closed position by solid lines, and in the opened position by dash lines. This view also shows the edge bulb in an up position by solid lines and in a down position by dash lines.

Figure 8 is a schematic sectional view showing variations that can be given to the contour of the cover plate.

Figure 1 shows the lickerin cover 4 and scavenger roll 6, of a conventional card along with the lickerin 1, feed roll 2, feed plate 3, nose 3a of the feed plate, and parts of the main cylinder 8. The scavenger roll has a felt covering, and rotates as the feed roll turns, to seal the opening between the feed roll and cover, and to pick up all loose fibers which tend to pass through.

The feed roll turns at a slow speed, normally about 1 or 2 revolutions per minute, and the scavenger roll is turned by its contact with the feed roll.

As seen in Figure 2, the apparatus of our invention is a cover plate 14, which fits above the lickerin 1, and has a contour which extends over the feed roll 2 and down to the surface of the fiber lap 9. The cover plate 14 replaces cover plate 4 and scavenger roll 6 of

Figure 1. Cover plate 14 is mounted on shrouds (not shown) which are the conventional end covers for the lickerin. The cover plate, provided with mounting holes 5a, is fastened to the shrouds by one cap screw 5 at each end which is the same method used to fasten the conventional cover plate 4, as seen in Figure 2. Cover plate 14 can have a variety of contours as shown by 19, 20, and 21 in Figure 8, and can be a single one piece cover with no hinged sections or adjustments. The preferred contour is 20 of Figure 8 which is also that of the

cover plate shown in Figure 2. The preferred cover plate has a hinged section 16 which has a beveled joint 16a, and a hinge 15, at each end. The hinged section is shown in the opened position 17, in Figures 2 and 7. It is held in the open position by resting in the groove 18 of the end closure pieces 10. It can be seen in Figures 2 and 7 that when the hinged section is in the opened position it exposes the feed roll for inspection where the lap feeds in, and it also by its position forms a closure for the space between the cover and the feed roll, thus preventing the escape of air and lint. When the hinged section 16 is in the closed position it rests against the curved surface of the end closure piece 10 and is held in posi-

tion.

tion by the hinges and its own weight. The end closure piece is fastened to the main section of the cover by the screws 11.

The preferred cover plate also has an adjustable bulb shaped edge piece 12, which can be adjusted up or down to regulate the pressure on the fiber lap. The adjustment is accomplished by loosening the nuts 13, Figure 7, and sliding the bulb up or down as permitted by the elongated holes 13a through which it is fastened.

The advantages of the lickerin and feed roll cover over the conventional cover and scavenger roll are as follows. By permitting the escape of air from above the lickerin and permitting the air to escape at the bulb shaped edge of the cover and through the uncompressed batt there is less air circulated with the lickerin past the mote knives 7 resulting in better removal of foreign matter with less loss of fiber. Also, by causing the escaping air to pass through the fiber lap as indicated by the arrows in Figure 2, the lint and dust are filtered out thereby keeping the room atmosphere clean. The lint and dust are fed back in with the fiber lap and the lint processed, and the dust is eventually discharged into the waste.

Tests with this invention show a reduction in neps in the card web. Neps are small tangled mats of fibers that will not process and by their presence lower the quality of the finished textile product. Neps are particularly objectionable in dyed fabrics since they always dye a different shade and can thereby give cause for the fabrics to be classed as seconds.

The following table presents test data obtained for purposes of comparison between our invention and a conventional lickerin cover with the scavenger roll. For the tests, low middling grade, 1½ inch cotton was used as the processing material:

and a feed plate the nose of which is in proximity to the feed roll, said contoured cover plate being of such dimensions as to completely cover the exposed top of the lickerin and to extend over and around the feed roll to a distance from the feed plate sufficient that the lower edge of the contoured cover plate makes contact with a fiber lap on the feed plate when in operating position, said fiber lap completing the closure between said lower edge of the contoured cover plate and the feed plate, whereby air currents generated during rotation of the lickerin and dust and lint carried by said air currents are directed into the fiber lap, said dust and lint being filtered and retained by said fiber lap while air passes through said fiber lap.

3. The contoured cover plate of claim 2 having means to adjust the position of the lower edge thereof whereby the pressure of said lower edge on the fiber lap can be varied.

4. In combination with a carding machine having a carding cylinder, a lickerin, a feed roll, and a feed plate having the nose thereof in proximity to the feed roll, a contoured cover plate over the lickerin and feed roll, said contoured cover plate completely covering the exposed top of the lickerin and extending over and around the feed roll to a distance from the feed plate sufficient that the lower edge of the contoured cover plate makes contact with a fiber lap on the feed plate when in operating position,

5. The contoured cover plate of claim 2 having means to adjust the position of the lower edge thereof whereby the pressure of said lower edge on the fiber lap can be varied.

6. In combination with a carding machine having a carding cylinder, a lickerin, a feed roll, and a feed plate having the nose thereof in proximity to the feed roll, a contoured cover plate over the lickerin and feed roll, said contoured cover plate completely covering the exposed top of the lickerin and extending over and around the feed roll to a distance from the feed plate sufficient that the lower edge of the contoured cover plate makes contact with a fiber lap on the feed plate when in operating position,

7. The contoured cover plate of claim 2 having means to adjust the position of the lower edge thereof whereby the pressure of said lower edge on the fiber lap can be varied.

8. The contoured cover plate of claim 2 having means to adjust the position of the lower edge thereof whereby the pressure of said lower edge on the fiber lap can be varied.

9. The contoured cover plate of claim 2 having means to adjust the position of the lower edge thereof whereby the pressure of said lower edge on the fiber lap can be varied.

10. The contoured cover plate of claim 2 having means to adjust the position of the lower edge thereof whereby the pressure of said lower edge on the fiber lap can be varied.

11. The contoured cover plate of claim 2 having means to adjust the position of the lower edge thereof whereby the pressure of said lower edge on the fiber lap can be varied.

12. The contoured cover plate of claim 2 having means to adjust the position of the lower edge thereof whereby the pressure of said lower edge on the fiber lap can be varied.

13. The contoured cover plate of claim 2 having means to adjust the position of the lower edge thereof whereby the pressure of said lower edge on the fiber lap can be varied.

14. The contoured cover plate of claim 2 having means to adjust the position of the lower edge thereof whereby the pressure of said lower edge on the fiber lap can be varied.

15. The contoured cover plate of claim 2 having means to adjust the position of the lower edge thereof whereby the pressure of said lower edge on the fiber lap can be varied.

16. The contoured cover plate of claim 2 having means to adjust the position of the lower edge thereof whereby the pressure of said lower edge on the fiber lap can be varied.

17. The contoured cover plate of claim 2 having means to adjust the position of the lower edge thereof whereby the pressure of said lower edge on the fiber lap can be varied.

18. The contoured cover plate of claim 2 having means to adjust the position of the lower edge thereof whereby the pressure of said lower edge on the fiber lap can be varied.

19. The contoured cover plate of claim 2 having means to adjust the position of the lower edge thereof whereby the pressure of said lower edge on the fiber lap can be varied.

20. The contoured cover plate of claim 2 having means to adjust the position of the lower edge thereof whereby the pressure of said lower edge on the fiber lap can be varied.

21. The contoured cover plate of claim 2 having means to adjust the position of the lower edge thereof whereby the pressure of said lower edge on the fiber lap can be varied.

22. The contoured cover plate of claim 2 having means to adjust the position of the lower edge thereof whereby the pressure of said lower edge on the fiber lap can be varied.

23. The contoured cover plate of claim 2 having means to adjust the position of the lower edge thereof whereby the pressure of said lower edge on the fiber lap can be varied.

24. The contoured cover plate of claim 2 having means to adjust the position of the lower edge thereof whereby the pressure of said lower edge on the fiber lap can be varied.

25. The contoured cover plate of claim 2 having means to adjust the position of the lower edge thereof whereby the pressure of said lower edge on the fiber lap can be varied.

26. The contoured cover plate of claim 2 having means to adjust the position of the lower edge thereof whereby the pressure of said lower edge on the fiber lap can be varied.

27. The contoured cover plate of claim 2 having means to adjust the position of the lower edge thereof whereby the pressure of said lower edge on the fiber lap can be varied.

28. The contoured cover plate of claim 2 having means to adjust the position of the lower edge thereof whereby the pressure of said lower edge on the fiber lap can be varied.

29. The contoured cover plate of claim 2 having means to adjust the position of the lower edge thereof whereby the pressure of said lower edge on the fiber lap can be varied.

30. The contoured cover plate of claim 2 having means to adjust the position of the lower edge thereof whereby the pressure of said lower edge on the fiber lap can be varied.

31. The contoured cover plate of claim 2 having means to adjust the position of the lower edge thereof whereby the pressure of said lower edge on the fiber lap can be varied.

32. The contoured cover plate of claim 2 having means to adjust the position of the lower edge thereof whereby the pressure of said lower edge on the fiber lap can be varied.

33. The contoured cover plate of claim 2 having means to adjust the position of the lower edge thereof whereby the pressure of said lower edge on the fiber lap can be varied.

34. The contoured cover plate of claim 2 having means to adjust the position of the lower edge thereof whereby the pressure of said lower edge on the fiber lap can be varied.

35. The contoured cover plate of claim 2 having means to adjust the position of the lower edge thereof whereby the pressure of said lower edge on the fiber lap can be varied.

¹ Cylinder and Doffer.

NOTES.—All percent figures are based on the net weight of cotton fed the machine.

We claim:

1. In combination with a carding machine having a carding cylinder, a lickerin, a feed roll, and a feed plate having the nose thereof in proximity to the feed roll, a contoured cover plate over the lickerin and feed roll, said contoured cover plate completely covering the exposed top of the lickerin and extending over and around the feed roll to a distance from the feed plate sufficient that the lower edge of the contoured cover plate makes contact with a fiber lap on the feed plate when in operating position, said fiber lap completing the closure between said lower edge of the contoured cover plate and the feed plate, whereby air currents generated during rotation of the lickerin and dust and lint carried by said air currents are directed into the fiber lap, said dust and lint being filtered and retained by said fiber lap while air passes through said fiber lap.

2. A contoured cover plate for the lickerin and feed roll of a carding machine having a lickerin, a feed roll,

50. through said lap thereby maintaining a constant pressure above the nose of the feed plate and feed roll at all lickerin speeds, the portion of the contoured cover plate covering the feed roll having hinges connecting it to the remainder of said contoured cover plate, said hinges being adapted to raise the hinged edge of said portion and to permit the edge in contact with the fiber lap to swing inward to contact the feed roll whereby said portion can be raised to expose the feed roll, said portion when raised forming a closure between the feed roll and the remainder 55. of the contoured cover plate to prevent escape of air and lint and dust carried by the air.
